Atty.

UNITED STATES PATENT OFFICE

2,546,753

BRAKE SLACK ADJUSTER

Malcolm S. Johnson, Chicago, Ill., assignor to
Illinois Railway Equipment Company, Chicago,
Ill., a corporation of Illinois

Application October 20, 1947, Serial No. 780,989

7 Claims. (Cl. 287—58)

1

My invention relates to a slack adjuster or take-up in the brake rigging of railway cars and more particularly freight cars and has for its object the provision of a rigid member pivotally connected to the upper end of the dead lever of the brake rigging and said member adjustably secured to the car underframe or center sill.

A further object of the invention is the provision of means for adjustably securing said rigid member to the car undersill so as to provide the usual normal or predetermined slack in the brake rigging in any of the adjusted or slack take-up positions of the dead lever and said rigid controlling fulcrum providing member.

Another object of the invention is the provision of a finger operated locking element, for holding the dead lever controlling member in its various positions, which has interlocking engagement with the holding means or housing secured to the car center sill so as to be non-removable while in assembled condition; a finger operated element which may be manipulated or released from its holding position from the car end without necessity for the operator to get beneath the car and which automatically will move to its holding or locking position.

A further object of the invention is the provision of a holding means or supporting housing whereby the rigid lever controlling member or pull rod may have lateral play or swinging movement in keeping with the movement of car truck about track curves so as to eliminate any binding action on the pull rod and associated elements; my improved structure also obviates the necessity of removing holding pins as employed in previous slack adjusters.

The foregoing objects and advantages, as well as other advantages inherent in my improved structure, will all be readily comprehended in the detailed description of the accompanying drawings wherein—

Figure 1 is a plan view of my improved structure shown attached to a portion of a car center sill, with an intermediate portion of the pull rod broken away.

Figure 2 is a side elevation with an intermediate portion of the operating or pull rod broken away and its inner end shown pivotally secured to the upper end of a dead lever of which a portion is shown.

Figure 3 is a sectional view on an enlarged scale taken on the line 3—3 of Figure 1 and substantially centrally through the supporting housing and outer end of the pull rod.

Figure 4 is a somewhat similar view with the locking pin in inoperative position and the pull rod removed.

Figure 5 is a front end elevation with the pull rod and locking pin removed.

2

Figure 6 is a sectional view taken on the line 6—6 of Figure 4.

Figure 7 is a sectional view taken on the line 7—7 of Figure 3 with the pull rod removed.

Figure 8 is a perspective view of the locking pin.

The invention, as exemplified in the drawings, comprises a suitable housing or bracket 15 formed at its top with a laterally disposed flange 16 whereby the housing is dependably secured in any suitable manner or by rivets to the lower flange of the car center sill of which a portion is shown at 17, so as to be disposed preferably toward one side of the sill as shown in Figure 1. The lower part of the vertical wall of the housing 15 is laterally enlarged to provide the spaced side walls 18, 18, see Figures 5 and 6, and the lower ends united with each other by the bottom wall 19 which is shown preferably extending longitudinally beyond the side wall portions 18, 18, as shown in Figure 6, substantially in keeping with the length of the housing above the bottom wall.

The spaced side walls 18, 18 and the spaced bottom wall 19 provide a channel 20 (see Figures 4 and 5) extending lengthwise from end to end 25 of the housing 15 to slidably receive a pull rod 21 therein.

The side walls 18, 18 preferably are reenforced by the vertical webs or ribs 22, 22, which extend from the top of the housing and into the bottom wall 19, and side walls 18, 18 at opposite ends 30 preferably are somewhat flared, as shown at 18a, more clearly seen in Figure 6.

The outer or front end of the housing above the channel 20 is provided with a vertically disposed socket at 23 which communicates at bottom with the channel 20 and is open to the outer or front end of the housing and there provided with opposingly disposed flanges 24, 24, see Figures 5 and 7.

The wall of the housing immediately above the channel 20 is provided with a longitudinally disposed slot 25 extending from the bottom of the vertical socket 23 and open at the front or outer end of the housing 15 and terminating at 45 the inner end wall 26 of the housing as shown in Figures 3 and 4.

The bottom wall 19 of the housing is provided with an elongated closed ended slot 27 which preferably is somewhat enlarged at the front or outer end of the housing beneath the vertical socket 23, see Figure 4.

The pull rod 21, which is of suitable length, at its outer end is formed with a flat-faced horizontally disposed portion 28, adapted to slidably fit into the longitudinal channel 20 in housing 15, and provided with a plurality of equidistant holes as at 29. The outer end of the pull rod terminates in an angular hand grasping portion 30 disposed laterally toward one side of the pull rod as shown in Figure 1; while the inner end

of the pull rod terminates in an apertured bifurcated or clevis like portion 31 which is arranged at a suitable angle of approximately 40 or 45 degrees to receive the upper end of the tilted brake rigging dead lever whose upper end is shown at 32, Figure 2, and is secured to the pull rod by a suitable pin as at 33.

The housing 15 is provided with a locking member or pull rod holding pin 34 shown in perspective in Figure 8 and formed with a cylinder shank or body portion 35, preferably beveled or tapered at its lower end, while the upper end is provided with the laterally off-set head 36 having vertical shoulders as at 37. The shouldered end of the head is provided with a finger grasping portion 38 which extends laterally from the head intermediate the shoulders 37, 37; with the lower longitudinal edge of the finger grasping portion 38 formed on opposite sides with outwardly extending flanges 39, 39. The main body portion of the pin 34, when in inoperative or pull rod released position, is adapted to slide upwardly into the vertical socket 23 while the finger grasping portion 38 extends outwardly through the open side of socket 23 between the opposingly facing flanges 24, 24; at which time the shoulders 37, 37 engage the inner faces of flanges 24, 24 and thus prevent removal of the pin 34. The length of the shank portion 35 of the pin is such that it will extend through a hole 29 in the pull rod and into the slot 27 in the bottom wall of the housing when the hole is brought into vertical alignment with the bottom of the socket 23, allowing the pin to automatically drop into holding position. When the pin 34 is in pull rod locking position, its flanges 39, 39 will extend into close proximity to the side walls of the channel 20 and prevent rotative movement of the pin.

When the adjuster is in its initial condition, namely with new brake shoes and truck wheels, the pull rod 21 is at its extreme inward position as shown in Figures 1 and 2, with the first hole 29 at the left hand or outer end of the pull rod adapted to receive pin 34; the latter being positioned in the vertical socket 23 until the end hole 29 comes into register with the bottom of the socket; the pin then moving inwardly with the pull rod until the pin engages the inner closed ends of the horizontal slots 25 and 27, which latter are of length commensurate with the normal movement or slack in the brake rigging. As undue slack in the brake rigging occurs, namely beyond the normal travel, the operator grasps handle 30 and pulls rod 21 outwardly, lifts pin 34 into socket 23 and continues pulling rod 21 farther outward until the next or succeeding hole 29 comes into register with the pin so it drops into the hole and then releases the pull rod, allowing its inward movement with the pin into the position shown in Figure 3, where the initial operative position of the pin is shown in dotted lines.

After the housing 15 has been properly secured or riveted to the bottom of the car center sill, holding or locking pin 34 is then inserted through the outer open end of the housing by inserting the main portion or shank 35 into the slot 27 in the bottom wall. The pin is then slid upwardly into socket 23 by means of finger grasping portion 38 which extends outwardly through the forward open end of the housing; the pin 34 being held in its raised position until the pull rod has been inserted in the channel 20 of the housing. The pull rod is inserted from the rear end of the housing by first introducing the hand grasp-

ing end 30 which, by reason of the comparatively narrow lower side walls 18, 18, may be readily inserted into the end of channel 20 and angled about a side wall 22, with the lower flat face of the apertured portion 28 of the pull rod slidingly resting on the bottom wall of the housing. After the yoke or clevis end 31 of the pull rod 21 has been pivotally secured to the dead lever 32 of the brake rigging, pull rod 21 is then pulled outwardly sufficiently to bring the first hole 29 beneath the bottom of vertical socket 23, allowing the pin to drop down through the hole with its lower end extending into the bottom slot 27; the operation of the pull rod and pin being repeated, when undue slack in the brake rigging occurs, until the last hole in the pull rod is brought into position to receive the pin, which position will indicate that the wheel and brake shoe have worn beyond the point of safety and efficient brake operation.

As is apparent from the structure shown and described, necessity for the operator to get beneath the car to adjust the connecting pins between the dead levers and the lever pull means, as in structures heretofore employed, is eliminated as adjustments with my improved slack adjuster may all readily be made at the ends of the car. With the comparatively narrow lower side walls 18, 18, beveled as shown in Figure 6, the rigid pull rod may swing laterally in keeping with the movement of the truck about a curve in the track and thus prevents binding action on the pull rod or truck lever; the beveled side walls 18, 18 providing an adequate flare adjacent the ends of the pull rod holding channel 20 in the housing.

The specific construction of my invention has been described in terms of description and not as terms of limitation, as structural modifications are possible and may be made without, however, departing from the spirit of my invention as defined in the appended claims.

What I claim is:

1. A brake slack adjuster comprising a housing adapted to be immovably secured to a railroad car under sill, provided with a horizontal channel extending from end to end of the housing and a vertically disposed socket connected with one end of said channel, the lower wall of the channel having a longitudinal closed ended slot of predetermined length commensurate with the normal slack in the brake rigging; a pull rod slideable in said channel, with its inner end adapted to be pivotally connected with the dead lever of the car brake rigging and the portion of the pull rod which is slideable in the housing provided with a plurality of longitudinally spaced holes; and a locking pin initially mounted in said socket and adapted to pass through the holes in the pull rod and into said closed ended slot when the holes successively are brought into register with said socket, whereby the pull rod is locked in its slack take-up positions and the pull rod and pin permitted to travel in said channel a distance commensurate with the normal slack in the car brake rigging.

2. A brake slack adjuster comprising a housing adapted to be immovably secured to a railroad car center-sill, provided with a horizontal channel extending therethrough with the bottom wall of the channel having a closed ended slot of predetermined length and having a vertical socket above the channel connecting with the latter, the outer wall of said socket being vertically slotted; a pull rod slideable in said channel,

with its inner end arranged to have pivotal connection with the dead lever of the car brake rigging while the opposite end of the pull rod terminates in a laterally disposed hand grasping portion and the pull rod adjacent the last mentioned end provided with a plurality of longitudinally spaced holes; and a locking pin initially mounted in said socket and provided at its upper end with a laterally disposed finger grasping portion arranged to slidably extend through the slotted wall of the socket, said pin being adapted to extend through the holes in the pull rod and into said closed ended slot whereby the pull rod is locked in its slack take-up positions when the holes in said rod are successively brought into register with the bottom of said pin and the rod and pin permitted longitudinal movement in the channel commensurate with the normal slack in the brake rigging.

3. In a brake slack adjuster, a housing with a slideway for receiving a brake rigging lever controlling rigid pull rod and provided with a vertically disposed socket at one end whose outer wall is vertically slotted, the bottom of said socket communicating with the pull rod slideway, the housing above said slideway and intermediate the housing and walls being provided with a locking pin-head receiving narrow longitudinal slot communicating with the slideway; and a vertically movable and self-seating pull rod locking pin initially arranged in said socket and provided with a head portion whereby removal of the pin is prevented, said head portion having a finger grasping portion extending laterally through the slotted wall of said socket when the pin is in its initial position, said head portion with the finger grasping portion being slidable in said longitudinal slot during longitudinal movements of the pull rod and rotation of the pin prevented.

4. In a brake slack adjuster, a housing for slidably receiving a brake lever controlling pull rod, provided with a vertically disposed socket extending upwardly from the pull rod slideway, an outer wall of said socket being vertically slotted with the side walls of the slot provided with opposingly facing flanges; and a vertically disposed pull rod locking pin initially seated in said socket, the upper end of said pin having a head provided with a finger grasping portion disposed through the slotted wall of said socket, the pin-head and finger grasping portion being formed to have sliding engagement with opposite sides of said flanges and removal of the pin prevented.

5. A brake slack adjuster comprising a rigid pull rod one end whereof is adapted to be secured to the end of the dead lever of a railroad car brake rigging, said rod adjacent its outer end being provided with longitudinally spaced holes; a housing, adapted to be rigidly secured to the car center sill, provided with a longitudinal channel extending therethrough and a lengthwisely slotted bottom wall connected to the housing by side walls tapering outwardly at opposite edges to provide flaring sides toward opposite ends of the channel whereby the pull rod may angle laterally; a vertically disposed socket in the housing above the channel with its lower end communicating with the channel, the outer side wall of the socket being vertically slotted; and a vertically movable locking pin arranged in said socket adapted to pass through the registered hole in the pull rod and into the bottom slot whereby the pull rod is held in adjusted position and permitted predetermined longitudinal

movement in keeping with the length of said bottom slot, said pin at its upper end having a laterally disposed finger grasping extension extending through the slotted wall of said socket whereby the pin may be lifted out of the pull rod holes without removal of the pin from the socket.

6. A brake slack adjuster comprising a housing having top, bottom and end walls, adapted to be rigidly secured to a railroad car under-sill and provided in its bottom with a channel extending therethrough from end to end, the bottom wall having an elongated slot while the upper wall of the channel is provided with a longitudinal slot communicating with the channel, extending from the outer forward end wall of the housing and terminating short of the inner or rear end of the housing, said slot at the forward wall of the housing terminating in a vertically disposed socket extending upwardly; a vertical slot through the forward wall disposed throughout the length of said socket; a pull rod adapted at its inner end to be pivotally secured to a lever of the brake rigging, said rod being slidable through said channel and provided with a plurality of longitudinally spaced openings; and a self-seating pin initially movable in said socket, provided at its top with an elongated finger grasping head adapted to extend through said vertical slot, said pin being adapted to drop through the openings in said pull rod when the openings are successively brought into alignment with the bottom of said socket.

7. In a brake slack adjuster for the brake rigging of a railroad car, a rigid pull rod with a plurality of longitudinally spaced engaging surfaces; a bracket housing provided with top, bottom, side and end walls for slidably mounting said pull rod, the lower end of the housing having a pull rod receiving slideway extending from end to end, a longitudinal slot above said slideway and in communication therewith and a vertical socket at one end of the slideway and communicating at its bottom with said slideway and having a vertical slot in its outer side wall, and a finger controlled vertically movable self-seating pin with a laterally extending finger grasping portion mounted in said vertical socket with its finger grasping portion initially extending through said vertical slot and arranged to slide in said longitudinal slot above said slideway and permit slackening off of the brake mechanism, the walls of said longitudinal slot and said pin being formed to prevent rotative movement of the pin, said pin being operable from the bracket housing exterior when the pull rod is drawn outwardly and adapted to successively effect locking engagement with the respective engaging surfaces of the pull rod during the slack take-up positions of the latter; the bracket housing being formed to permit the pull rod with the locking pin to have predetermined longitudinal movement.
